(57) **CLAIM**

The ornamental design for bonded panel having interlocking sides, as shown and described.

DESCRIPTION

FIG. 1 is a perspective view of a bonded panel having interlocking sides showing a first embodiment of my new design; the broken line showing of a second bonded panel is for illustrative purposes only and forms no part of the claimed design.

FIG. 2 is front elevational view of FIG. 1;

FIG. 3 is a right side elevational view of FIG. 1;

FIG. 4 is a left side elevational view of FIG. 1;

FIG. 5 is a top plan view of FIG. 1, the bottom plan view being a mirror image thereof;

FIG. 6 is an enlarged partial view, looking from the top of FIG. 1, illustrating the cooperation of the sides of adjacent bonded panels while they are being brought together or taken apart;

FIG. 7 is an enlarged partial view, looking in the direction of arrows 7—7 in FIG. 6;

FIG. 8 is a top plan view of a second embodiment of the bonded panel of the present invention, having straightened ends on the left side; the right side thereof being identical to that shown in FIG. 1;

FIG. 9 is an enlarged partial elevational view, looking in the direction of arrows 9—9 in FIG. 8; and,

FIG. 10 is an enlarged partial perspective view, looking in the direction of arrows 9—9 in FIG. 8.

The bonded panel having interlocking sides is shown as broken in FIGS. 1-4 to indicate indeterminate length and in FIG. 6 to indicate indeterminate width.
